(57) **CLAIM**

The ornamental design for a fishing rod handle clamp as shown and described.

DESCRIPTION

FIG. 1 shows a perspective view of the invention;

FIG. 2 shows a front view thereof;

FIG. 3 shows a side view thereof;

FIG. 4 shows a top view thereof;

FIG. 5 shows a side-perspective of the invention inside a sleeve which is represented in dashed lines the sleeve forming no part of the claimed invention; and,

FIG. 6 shows a side-perspective of the invention partially extended out of a sleeve which is represented in dashed lines the sleeve forming no part of the claimed invention.
